UNITED STATES PATENT OFFICE.

JACOB A. KRESS, OF CANTON, OHIO.

RAZOR-SHARPENER.

1,106,717.

Specification of Letters Patent. Patented Aug. 11, 1914.

Application filed November 9, 1912. Serial No. 730,337.

To all whom it may concern:

Be it known that I, JACOB A. KRESS, a citizen of the United States, residing at Canton, in the county of Stark and State of Ohio, have invented a new and useful Razor-
5 Sharpener, of which the following is a specification.

My invention relates to improvements in means for stropping the blades of razors and the like, the blade being supported by an oscillating blade holder actuated by a reciprocating strop.

The objects of the invention are to generally improve devices of the character mentioned and to provide a thoroughly efficient razor sharpener by an appropriate combination of elements hereinafter described and distinctively pointed out in the appended claims. These objects, together with other 10 objects apparent to those skilled in the art, may be attained by the construction illustrated in the accompanying drawings, although the invention may be embodied in other forms, the construction illustrated being chosen by way of example.

In the drawings Figure 1 is a perspective view of the razor sharpener embodying my invention, the blade of the razor being shown arranged therein and parts being 15 broken away. Fig. 2 is a perspective view of the sharpener frame, the strop and blade holder being omitted. Fig. 3 is a longitudinal, vertical, sectional view through a razor sharpener embodying my invention. Fig. 4 is a top view. Fig. 5 is a horizontal sectional view on the line 5—5 of Fig. 3 showing the parts in the position assumed when the strop is moving in one direction. Fig. 6 is a similar view on the line 6—6 of Fig. 20 3 showing the parts in the position assumed when the strop is moving in the other direction. Fig. 7 is a perspective view of the blade holder. Fig. 8 is a vertical sectional view of the same. Fig. 9 is a perspective view of the blade-holder-actuating roll. Fig. 10 is a perspective view of the blade-holder-returning spring.

Throughout the several views similar reference numerals indicate similar parts.

50 More specifically describing the construction disclosed in said drawings the numeral 1 indicates the upper frame plate, the numeral 2 the lower frame plate, said plates being connected by the integral yoke 3 to which is pivotally connected the attaching ring 4 by which the device may be fas-

tened to a hook or other stationary support. The plates 1 and 2 and the yoke 3 are preferably stamped from a single piece of sheet metal of sufficient thickness to insure 60 strength and rigidity. The said plates 1 and 2 are, in general, parallelly disposed, the lower plate 2 being considerably longer than the upper plate 1.

The upper plate 1 is provided with the 65 razor opening 5, the rear end of which opening is somewhat spaced from the yoke 3. By reason of said opening 5 the upper plate 1 is thus provided with the two upper side pieces 6 and the upper front piece 7. In 70 a somewhat similar manner the lower plate is provided with an opening 8, the rear end of which is spaced farther from the yoke 3 than the rear end of the opening 5, said opening 8 producing in the lower plate the 75 lower side pieces 9 and the lower front piece 10.

For the purpose of fixedly connecting the front ends of the plates 1 and 2 the two connecting and spacing bars 11 are provided, 80 each of said bars being connected to the upper front piece 7 and to the lower front piece 10 in a fixed, permanent manner. It will be noted that said bars 11 assume an inclined position with reference to the nor- 85 mally vertical yoke 3.

At the rear ends of the openings 5 and 8 are the upper and lower blade-holder-attaching ears 12 and 13 respectively. These ears are formed integrally with the plates 90 1 and 2 and are bent upwardly at an angle with reference to said plates, said ears, however, being parallel with each other and the lower ear 13 being considerably in advance of the upper ear 12.

The blade holder is preferably formed from a single sheet of spring steel and comprises the back 14 and the integral clamping flanges 15 and 16, which converge toward their free edges opposite the back 14 100 and are adapted to clamp the blade of a razor such as shown at 17, in the drawings, permitting the cutting edge of the razor to protrude beyond the free edges of said flanges. The flange 15 is provided with an 105 integral stop lug 18 at the bottom end thereof, which lug is bent over across the lower end of the flange 16 to form a stop to prevent the point of the razor blade from protruding beyond the lower end of the holder. 110 Formed integrally with the lower end of the back 14 is the lower holder arm 19 pro-

vided with an aperture 20 and with a pair of upwardly turned, inwardly directed spring holding lugs 21 for the purpose hereinafter more fully disclosed. At the upper 5 end of said back the integral upper holder arm 22 is provided, said arm having an aperture 23 intermediate its ends, and the free end of said arm provided with an integral, inverted-cup-shaped head 24, the outer edges of which are rounded to produce a bearing surface. Extending from the ear 12 to the ear 13 is the blade-holder-attaching bar 25, said bar passing through the apertures 20 and 23 in the lower and upper 10 holder arms 19 and 20 respectively. In this manner the razor holder is pivotally mounted in the frame in inclined position corresponding substantially to the inclination of the bars 11.

20 Between the flanges 15 and 16 and connected to the back 14 are the upper and lower blade pressing springs 26 and 27. The spring 27 is connected to the back 14 by a single rivet at its lower end, the upper 25 end of said spring 27 being free from said back and normally spaced therefrom. The upper spring 26 is connected at its upper end to the back 14 and its lower free end overlies the spring 27, as clearly illustrated 30 in Figs. 3 and 8. The purpose of these springs is to hold the blade of a razor in proper position between the flanges 15 and 16 so that the cutting edge thereof will protrude from the holder and be held in proper 35 position.

The blade-holder-returning spring is preferably formed of wire and of the form illustrated in Fig. 10 comprising a coil 28 of one and one-half turns and the integral free ends 40 29. The coil 28 is arranged around the bar 25 and the ends 29 are brought under the spring holding lugs 21, the said spring being thus held down in place adjacent the holder arm 19. Preferably stamped from the lower 45 frame plate 2 are two raised, spaced, inwardly turned lugs 30 adapted to loosely engage the ends 29 to prevent outward, side movement of said ends when the blade holder is oscillated.

50 The blade holder actuating roll is preferably stamped from sheet metal and comprises the incomplete hollow cylinder 31 having the spaced edges 32, integral portions of the metal being bent over at the ends to form the end flanges 33 provided with apertures 34 adapted to rotatably receive the roll-attaching rod 35, which is connected to the upper and lower plates 1 and 2 in position parallel to the yoke 3. The 55 edges 32 are forwardly disposed and receive between them the flange 24 at the free end of the upper arm 22 of the blade holder. It will be thus apparent that when the blade-holder-attacting roll is rotated in one direction the blade holder will be oscillated by

rotary movement about the bar 25 in the opposite direction, and vice versa. As the blade holder is oscillated to one side or the other the returning spring on the lower arm 19 will press firmly against one or other of the lugs 30 and will tend to return the holder to the intermediate position illustrated in Fig. 4.

70 The strop 36 is provided with suitable handles 37 at its two free ends and extends 75 around the blade-holder-actuating roll, being in immediate frictional contact therewith.

In using the device the handles 37 are 80 grasped in the two hands of the operator, the ring 4 having been attached to some 85 fixed support, and by pulling alternately on the two handles the strop is caused to reciprocate or move alternately in opposite 90 directions through the frame and around the roller. As shown in Figs. 5 and 6 the 95 blade holder will be actuated by the alternate opposite rotation of said roller to throw the edge of said blade into contact with that portion of the strop which is moving out frontwardly from the frame. The blade 100 holder being held in inclined position with relation to the strop, the preferred "heel to point" stropping effect will be produced, the blade holder being returned to the intermediate or neutral position by the operation of the spring ends 29 as soon as the forward movement of the strop has discontinued, thus effectually preventing any cutting of the strop by backward movement thereof 105 against the sharp edge of the blade.

110 It should be noted that the upper side pieces 6 and the lower side pieces 9, adjacent their forward ends are provided with integral guide-roller-attaching portions 38 bent out of the plane of the upper and lower 115 frame plates and into position at right angles to the line of inclination of the blade holder. Extending from each upper side piece to the corresponding lower side piece 120 and journaled in apertures in the portions 38 are the side, rotatable, guide rollers 39, so arranged as to engage the outer side of the strop in lines substantially corresponding to the lines of contact between the edge of the 125 razor blade and the inner side of the strop. The upper front piece 7 and lower front piece 10 are also bent out of the planes of the upper and lower frame plates 1 and 2 respectively, said pieces 7 and 10 lying in 130 planes parallel with the planes of the portions 38. Intermediate the bars 11 and journaled in the upper and lower front pieces is the rotatable guide roller 40 adapted to contact with said bars 11 in maintaining the strop in proper position within the frame and preventing the strop from contacting with the sharp edge of the razor blade when same is in the neutral position.

Especial attention is directed to the sim- 130

plicity and durability of the construction and the few parts comprising the device. The inverted-cup-shaped flange 24 provides a substantial, smooth, rounded bearing 5 against the spaced edges 32 of the blade-holder-actuating roll and the spring attached to the lower holder arm 19 is free and positive in its relation, being unhampered and capable of instantly returning the 10 blade holder to the neutral position when forward motion of the strop has ceased.

It will, of course, be understood that the razor blade is inserted into the holder from the top end thereof, the said blade being 15 pushed down until it engages the stop lug 18, whereupon the springs 26 and 27, together with the flanges 15 and 16 will hold 20 said blade firmly in position for the accurate stropping thereof.

20 I claim:—

1. In a razor sharpener of the character described, in combination with a frame, a blade holder pivotally mounted in said frame and provided with an arm having at 25 its free end an integral inverted-cup-shaped head with outer rounded edges forming a bearing surface and a blade-holder-actuating roll rotatably mounted in said frame, said roll comprising an incomplete hollow 30 cylinder having spaced edges engaging the bearing surface of said head, said roll, when rotated alternately in opposite directions, adapted to transmit reciprocating movement to said head.

35 2. In a razor sharpener of the character described, in combination with a frame provided with upper and lower frame plates and a blade-holder-attaching bar extending from one of said plates to the other, a 40 blade holder provided with arms pivotally connected to said bar, one of said arms provided with a pair of spring-holding lugs, and a spring formed from a piece of wire coiled about said bar and having two free 45 ends engaging and extending beyond said lugs, and spaced lugs on one of said frame

plates adapted to loosely engage the ends of said spring and prevent outward, side movement of said ends, said spring adapted to maintain said blade holder normally in the 50 median, longitudinal, vertical plane of said frame.

3. In a razor sharpener a blade holder formed from a single piece of sheet metal and comprising a back and integral clamping flanges extending frontwardly from said back and converging toward their free edges, one of said flanges provided with an integral stop lug at its lower end, said lug being bent over across the lower end of the 60 other flange, a lower integral arm extending rearwardly from the lower end of said back and provided intermediate its ends with an aperture and at its extreme end with a pair of upwardly turned, inwardly directed lugs, 65 an integral upper arm extending rearwardly from the upper end of said back, provided intermediate its ends with an aperture and the free end of said upper arm provided with an integral inverted-cup-shaped head 70 having outer rounded edges.

4. In a razor sharpener of the character described, a blade holder formed from a single piece of sheet metal and comprising a back and integral clamping flanges extending frontwardly from said back and converging toward their free edges, a blade 75 stop at the lower ends of said flanges, a pair of integral arms extending rearwardly from said back, said arms provided intermediate 80 their ends with apertures, one of said arms provided at its free end with spring engaging means and the other provided at its free end with a cup-shaped integral head providing an outwardly curved bearing surface. 85

In testimony that I claim the above, I have hereunto subscribed my name in the presence of two witnesses.

JACOB A. KRESS.
